THREADING APPARATUS

Charles H. Laemmel, Detroit, Mich., assignor, by
mesne assignments, to The Sheffield Corpora-
tion, Dayton, Ohio, a corporation of Ohio

Application April 29, 1948, Serial No. 23,999

2 Claims. (Cl. 10—95)

1

This invention relates to thread cutting tools. One object of the invention is the provision of a threading head having improved means for controlling the operation of a tool adjusting sleeve with respect to the holder in which the threading cutters are arranged, the construction being such that the sleeve is adjustable by a lever rotatable on a radial axis and having an eccentric pin operable in a transverse groove in the cutter holder which is also provided with a longitudinally extending pin receiving groove that permits retraction of the sleeve beyond its normal operating range in order that the threading cutters can be released and removed.

A further object of the invention is the provision of a threading die head having a control lever operable about an axis extending radially of the head and held against other than rotational movement, the lever being arranged for rotation beyond its normal opening and closing range of movement to permit retraction of the chaser adjusting sleeve to such an extent that the chasers can be removed from the holder.

Other objects and advantages of the invention will be apparent from the following description, the appended claims and the accompanying drawing, in which:

Fig. 1 is an end view of a threading head embodying the present invention;

Fig. 2 is a longitudinal section on the line 2—2 of Fig. 1;

Fig. 3 is a longitudinal section on an enlarged scale on the line 3—3 of Fig. 1;

Fig. 4 is a top plan view of the threading head showing the sleeve retracted to permit release of the chasers; and

Fig. 5 is a section on the line 5—5 of Fig. 3 and showing a portion of the holding plate.

Referring more particularly to the drawing in which the preferred embodiment of the invention has been illustrated in its association with a self-opening threading die head having radial thread chasers, 10 generally designates a chaser holding body having suitable slots supporting the chasers or tools 11 for radial sliding movement therein. Coil springs 12 acting on pins 13 carried by the chasers urge the chasers outwardly from the closed or threading position represented in Fig. 2 in the same manner as in the patent to France 1,777,380. An adjusting sleeve 15 is axially movable on the body 10 to open or release the chasers as in the patent just mentioned.

The body 10 preferably comprises a forward section 16 and a rear section 17 fixed to one another by suitable bolts, not shown, section 17 being slidably carried on the shaft 18 and urged towards the right on the shaft as viewed in Fig. 3, by means of springs 20. The left hand ends of springs 20 are received in recesses in a lateral projection 19 on the shaft 18. An adjustment nut 21 threaded on the shaft forms a stop against which the end of the body portion 17

2

engages. Lock nut 22 threaded on the rear part of the body portion 17 secures a threaded adjusting collar 23 in desired position so that when the relative axial movement of the work and the threading head is stopped during a threading operation, the continued rotation of one of those parts draws the threading head forwardly against the action of springs 20 to a predetermined point when the sleeve 15 is moved to the right and the dies are automatically opened by trip means of the character shown in the prior patent to France referred to. In addition to the springs 20 that are effective in the pull-off operation, springs 50 are provided in chambers 49 between a flange on the body section 16 and a flange of the sleeve 15, as shown in Fig. 2.

Closing movements of the die are effected under the control of the operator by means of an operating lever one portion of which constitutes a shaft 25 rotatably movable in the sleeve 15. The latter is preferably provided with a bushing 26 fitting in a cylindrical hole in the sleeve so that the shaft 25 can rotate about an axis extending radially of the threading head. Projecting laterally from the shaft 25 is an operating arm 27 which can be moved from a closed or threading position shown at A in Fig. 4 to an open position indicated at B. The handle 30 swings in a plane tangential to and above the die head so that pressure can very conveniently be applied by the operator in closing the die head. The shaft 25 is operably connected to the tool carrying body 10 by means of a projecting pin 29 which is at one side of the shaft axis. This pin operates in a transverse groove 30 in the body and the axial components of the pin's movements are effective to close the die when the handle 27 is moved from the position B to position A indicated in Fig. 4. When the head is automatically opened at the end of a threading operation, the handle swings back to position B as the sleeve 15 is moved rearwardly.

The shaft 25 is positively held against axial movement, while permitting its free rotation, by means of a holding plate 31 secured to the sleeve 15 as by means of a screw 32. The two legs 33 of this plate enter opposed transverse slots 34 in the bushing 26 to fix the bushing 50 against axial and rotational movement in the sleeve 15, legs 33 also entering the opposite sides of an annular groove 35 in the shaft 25 to permit rotation of the shaft while holding it in place against axial movement.

The swinging movements of the arm 27 are preferably limited in a positive manner by a stop pin 36 on shaft 25 which engages a shoulder 37 on the bushing 26 when the handle 27 swings towards the right some little distance beyond the position B shown in Fig. 4 but before it reaches a position in line with the shaft 18.

In accordance with the present invention the handle 27 may be swung beyond its normal oper-

ating range if the operator so desires, in order that the sleeve 15 may be moved towards the right far enough to entirely release the threading dies 11 from the body 10, without requiring the use of tools or disassembling any of the parts of the threading head. As previously mentioned, the stop pin 36 normally prevents this movement but pin 36 may, if desired, be intentionally depressed by the operator to permit continued travel of the arm 27. For this purpose the pin 36 is slidably carried in a radial bore and held in its normal projected position by means of a spring wire 39 arranged in an annular groove 40 in the shaft 25, the end of this spring pressing against a head 41 on the pin to normally hold the pin projected but permitting the pin to be moved back far enough so that it no longer engages the shoulder 37. The operator can thus move the handle to the position C shown in full lines in Fig. 4. In this position the projecting pin 29 on shaft 25 is moved to a position in line with an axially extending slot 43 in the body 10 and this permits the sleeve 15 to be moved towards the right as viewed in the drawing to the position shown in Fig. 4 in which the ends of the slots that carry the chasers are entirely uncovered so that the chasers can be moved for resharpening or inspection, without requiring the use of tools and without requiring the disassembling of any of the parts one from another. Complete disassembly of the sleeve 15 from the body can be effected by unscrewing the nut 21.

When it is desired to close the threading head after reinserting the chasers, it is merely necessary to enter the pin 29 in the longitudinal slot 43 with the arm 27 in the position shown in full lines in Fig. 4, and move the sleeve 15 forwardly until the pin 29 is in the transverse slot 30. The handle 27 can then be swung clockwise to the position B and then on to position A which will close the die head. Before the handle reaches the position B in moving from position C, the stop pin 36 will be uncovered and released so it may spring out to its normal position again from the retracted position in which it is held by the upper portion of the bushing 26.

As will now be apparent, the rotational movements of the shaft 25 move the pin only in the transverse slot 30 during the normal operating range between opening and closing position and it is only when the handle is rotated to a position beyond the normal operating range that pin 29 can enter the longitudinal slot 43 and permit full retraction of the sleeve on the body to release the dies. In accordance with this invention, it will be clear, since the handle swings in a plane which is tangential of the threading head, that the required power can be conveniently applied even in dies of considerable size.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A self-opening threading head comprising a body provided with means for guiding threading tools for opening and closing movements, a sleeve axially movable on said body through a normal operating range from opening to closing position of the tools, a rotatable shaft provided with a handle and an operating pin eccentric of the shaft axis, means on said sleeve rotatably

supporting said shaft for movement about an axis extending radially of the sleeve, means retaining said rotatable pin mounting shaft against movement along its axis, said body on its peripheral portion having a transverse groove receiving said pin so that the axial component of rotational movement of the pin in its normal operating range causes axial movement of the sleeve on the body, said body also having a pin receiving groove extending substantially axially of the body from a point on said transverse groove which is substantially beyond the pin's normal operating range of movement, the bottom of the axial pin receiving groove lying inwardly of the geometric plane in which the bottom of the pin moves during normal operation to cause axial movement of the sleeve, the size relationship of said shaft, pin and transverse and axial grooves being such that the pin is movable from the transverse groove to the axial groove by rotation of the shaft beyond the limit of its normal operating range whereby the sleeve is retracted beyond its normal operating range of movement to a point on the transverse groove substantially beyond the pin's normal operating range of movement.

2. A self-opening threading head comprising a body provided with means for guiding threading tools for opening and closing movements, a sleeve axially movable on said body through a normal operating range from opening to closing position of the tools, a rotatable shaft provided with a handle and an operating pin eccentric of the shaft axis, means on said sleeve rotatably supporting said shaft for movement about an axis extending radially of the sleeve, means positively retaining said rotatable pin mounting shaft against movement along its axis, manually releasable means positively stopping rotation of the shaft beyond a normal operating range, said body in its peripheral portion having a transverse groove receiving said pin so that the axial component of rotational movement of the pin in its normal operating range causes axial movement of the sleeve on the body, said body also having a pin receiving groove extending substantially axially of the body from a point on said transverse groove which is substantially beyond the pin's normal operating range of movement, the bottom of the axial pin receiving groove lying inwardly of the geometric plane in which the bottom of the pin moves during normal operation to cause axial movement of the sleeve, the size relationship of said shaft, pin and transverse and axial grooves being such that the pin is movable from the transverse groove to the axial groove by rotation of the shaft beyond the limit of its normal operating range whereby the sleeve is retracted beyond its normal operating range of movement to release the threading tools when the pin is moved to a point on the transverse groove substantially beyond the pin's normal operating range of movement.
